(57) **CLAIM**

The ornamental design for a photovoltaic energy storage cabinet, as shown.

DESCRIPTION

FIG. 1 is a front view of a photovoltaic energy storage cabinet showing our new design;

FIG. 2 is a rear view thereof;

FIG. 3 is a left side view thereof;

FIG. 4 is a right side view thereof;

FIG. 5 is a top plan view thereof;

FIG. 6 is a bottom plan view thereof;

FIG. 7 is a front perspective view thereof; and,

FIG. 8 is a rear perspective view thereof.
